UNITED STATES PATENT OFFICE

MARTIN J. TROY, OF ATLANTIC HIGHLANDS, NEW JERSEY

INK FOUNTAIN DIVIDER AND PAD

Application filed December 22, 1931. Serial No. 582,560.

This invention relates to fountain dividers as employed in connection with the ink feeding fountain on printing presses and in particular to a pad member employed in connection with a divider to partition the fountain so that inks of various colors may be used and fed to a fountain roller and sent to a ductor roller without the necessity of cutting the ductor roller.

10 A particular object of my invention is to provide a combination pad and strip which is so constructed that when it is used in connection with a dividing partition in an ink fountain, it will effectively prevent passage of ink from one side of the partition or divider to the other side and will maintain on the fountain roller in connection with which the pad is employed, zones which are free of ink thus maintaining on the fountain roller 20 clear spaces between the zones of colored inks.

In the present use of dividers in fountains of the character referred to, paper is employed for a stuffing or pad beneath the edges of the divider and on the circumference of 25 the fountain roller between the roller and the divider but the paper is objectionable because it shreds off due to ink absorption and it is necessary to shape the paper and use considerable pressure or force to do so. This force 30 often bends or buckles the fountain blade which makes the setting and feeding of the inks of various colors very difficult.

My invention eliminates also the cutting of the ductor roller because the fountain roller 35 is kept clean between the zones of colored inks and my device may be employed with a saving of time and labor inasmuch as it is already prepared and can be placed in position effectively and quickly.

40 Another object of my invention is to provide an adjustable divider which is used in connection with the pad and is arranged to jam the same against the fountain roller so that a leakproof partition is provided at 45 spaced points along the fountain roller for the accommodation of various colors of ink. I have also provided in connection with the divider, either of an adjustable type or of the present fixed type, as employed, a rocker 50 which when the divider is secured to the fountain, tends to throw the forward edge of the divider down and into the corner of the fountain where it meets the fountain roller with the result that a clearly defined, clean 55 zone between the various colored inks em-

ployed on the fountain roller is obtained.

Changes and variations may be made in the construction shown and described without departing from the principles of the invention or sacrificing its chief advantages; hence 60 such invention is not to be confined to the structures shown in the accompanying drawing; in which,

Figure 1 is a plan view of the strip portion of my pad and strip construction showing the formation of the tongue which is arranged to fit into the pad.

Figure 2 is a top plan view of the pad member forming a part of my invention.

Figure 3 is a view in side elevation of the 70 strip member illustrated in Figure 1.

Figure 4 is a view in side elevation of the pad member illustrated in Figure 2, the strip and the pad being combined to form a unitary 75 construction.

Figure 5 is an enlarged fragmentary view in sectional elevation of the lower end of the pad and strip member showing how the same are joined.

Figure 6 is a view in sectional elevation of 80 a fountain construction employing a divider and my improved dividing strip and pad.

Figure 7 is an enlarged section taken on the line 7—7 of Figure 6 and shows the method of preventing sidewise twisting of the divider. 85

Figure 8 is a section taken on the line 8—8 of Figure 6 and shows the grooved under surface of the divider and its connection with the pad.

Figure 9 is a section similar to Figure 8 and taken on the line 9—9 of Figure 6 to show the end of the divider and pad in contact.

Figure 10 is a fragmentary view of the fastening end of the divider made in a single piece, a part thereof being shown in section 95 to illustrate the use of a rocker in connection with the divider.

Figure 11 is a section taken on the line 11—11 of Figure 10 further showing the position of the rocker in the divider, and 100

Figure 12 is a view in perspective of the rocker piece which may be inserted in the present type of divider.

Referring to the drawing in detail, 5 indicates a strip consisting of a binder 6 of 105 any material such as buckram, for instance, interposed between strips of felt 7. The strip at one end is cut to provide a tongue 8 which is arranged to fit into the tongue bore 9 extending transversely through the pad 10. 110

This pad is constructed of two of the strips 5 cemented together as at 11 and consisting of the binder 6 interposed between the layers of felt 7. This pad 10 is arranged to have cemented in the opening 9 thereof previously referred to, the tongue 8 of the strip 5 and when this cementing as at 12 is accomplished, it forms at the lower end of the pad 10, a substantially firm point or apex, the lower end 10 of the pad 10 being bevelled as at 13 so that the point 14 fits into the corner formed by the junction of the fountain roller and the fountain blade, as will be hereinafter described. The strip 5 and the pad 10, when 15 secured together as described, constitute a unitary separator pad, as it will be herein-after referred to, which is arranged to be used in connection with the divider 15 of an ink fountain construction as commonly employed 20 in connection with the fountain roller 16 of printing presses, it being understood that the ink is fed out of the fountain trough to a fountain roller 16 from which it is taken by a ductor roller 17.

25 The usual ink fountain consists of the side or end walls 18 joined by the longitudinal strips 19 and 20 which in turn, are secured together by the bottom rib 21, any number of these ribs being employed depending upon 30 the length of the fountain. In order to feed to the fountain roller, a number of different colors of ink, it is necessary to divide the fountain itself by placing dividers or partitions therein to form individual ink troughs

35 but heretofore, difficulty has been encountered in keeping the inks separate and keeping them from leaking from one compartment into another and also in keeping the ink separate not only on the fountain roller but also on 40 the ductor roller and to this end, I have made the pad up as hereinbefore described which is positioned so that the pad portion 10 rests against the fountain roller while the strip portion 5 rests on the fountain blade 23, 45 which in turn, rests on the strips 19, 20 and on the bottom ribs 21 to form a bottom for the ink fountain, the forward end of the blade where it is slightly spaced from the mountain roller, being adjustably positioned through 50 the medium of a set screw 24 so that the feed of ink is controlled to the fountain roller.

This divider 15 is of substantially triangular formation and constitutes a compartment wall. It is grooved at its forward end as at 55 25 and along its lower end as at 26 so that the edges thereof bite into the fountain pad as illustrated in Figures 8 and 9 and thus prevent leakage of the ink from one side of the divider to the other. The fountain pad is 60 thoroughly oiled to act on the fountain roller as a continuous cleaning pad for the space between the zones of ink on said fountain roller. The divider 15 has a nose portion 27 which engages at the meeting point of the 65 strip 5 and the pad 10 so that it forces the

same down into the corner formed by the meeting of the fountain roller and the fountain blade and the pressure of the divider on the pad 10 clearly defines on the fountain roller, an uninked zone which separates the various colored inks and retains them so separated as they are transferred to the ductor roller. In order that the nose 27 of the divider 15 may be effectively thrust into the corner, use is made of a rocker 28 which may 70 be either secured to or formed as an integral part of the divider and which is situated near its outer end and across the bottom thereof the rocker resting on the strip 5 of the pad and being positioned further back than the 75 clamping screw 29 which is used in connection with the yoke 30 to secure the divider in place, the tightening of the screw 29 throwing the nose 27 of the divider down into the corner to effectively compress the strip 5 and prevent leakage in said corner. The yoke 30 is provided with an extension 31 in my 80 adjustable type of divider through which passes an adjusting screw 32, the extension 31 being positioned in a bore 33 formed in the divider 85 and into one side of which opens the slot 34 in which a pin 35 carried by the extension 31 is positioned to prevent sidewise rocking movement of the divider 15 when it is being 90 adjusted. Operation of the adjusting screw 95 32 will force the divider 15 down into position against the pad to effectively form a seal with the fountain roller.

An important feature of my invention is the use of the rocker and in order to provide it on existing dividers in present day use, I have illustrated the same in connection with Figures 10 to 12 inclusive in which is illustrated a divider made in a single piece, as indicated by the numeral 33 and having the 100 fastening yoke 34 thereon with its set screw 35 through the medium of which the divider 33 is held in position. The divider 33 is provided with a bottom groove 36 and into this 105 groove, I slide the rocker which consists of a semi-cylindrical piece 37, the overhanging edges of which 38, rest on the edges 39 bordering the slot 36 in the bottom of the divider, the one side of the member 37 also resting on the divider at the end of the slot 36 in that 110 portion indicated by the numeral 40. Secured to the cylindrical portion 37 is the block 41 which may be rectangular in shape and may be of a thickness to suit the depth of the slot so that the top of the block is flush with the bottom of the divider, a thin one being 115 illustrated in Figures 10 and 11 while the thicker type of block is illustrated in Figure 12, it being understood that the slot 36 is more or less standard and it is simply necessary to force fit the block in position in the slot 36 in the position illustrated in Figure 10 and the rocker will be in place to engage 120 the fountain pad or separator pad so that the divider will be thrown down as explained in 125

connection with the type of construction shown in Figure 6.

It is evident therefore, that I have provided a pad of felt which will not only stand wear but which will effectively shape itself to the contour of the fountain roller and the front edge of the divider and which eliminates the necessity of using force to make it conform to the shape, thereby preventing the bending or buckling of the fountain blade and the improper feeding of the ink.

My improved pad also eliminates the cutting of the ductor roller because the fountain roller is kept clean between the zones of the colored inks and the cementing of the strip member into the pad portion gives a relatively firm end which can be pushed down into the corner to prevent the leakage which has been always a problem and which invariably occurs at that point.

It is evident also that the groove in the bottom and front edge of the divider bites into the felt pad and prevents sidewise movement thereof. It also does away with the use of paper which has been objectionable and saves time and trouble.

My pad can also be made in a single piece in any manner or out of any material desired.

My invention is not to be restricted to the precise details of construction shown since various changes and modifications may be made therein without departing from the scope of the invention or sacrificing the advantages derived from its use.

What I claim is:—

1. A pad for use with an ink fountain compartment wall and roller to prevent leakage between compartments comprising a strip portion and a pad portion made of pliant material and means for joining said portions to provide a relatively firm point, between a corner of the compartment wall and the roller.

2. A pad for use with an ink fountain compartment wall and roller to prevent leakage between the compartments comprising a strip portion, a pad portion made of pliant, laminated material, and means for joining said portions to provide a relatively firm point, between a corner of the compartment wall and the roller.

3. A separator pad for use with an ink fountain compartment wall and roller to prevent leakage between compartments comprising strip portions of laminated, pliable material, one of the portions having a tongue, and one of the portions having an opening for the reception of said tongue, means for securing said tongue in said opening and said means providing a relatively firm portion in said pad, between a corner of the compartment wall and the roller.

4. In combination with an ink fountain including a fountain roller, a fountain blade and a support for the blade, of a separator for dividing the fountain into compartments, a pad interposed between the separator, the fountain blade and the fountain roller, means for securing the separator in position and a rocker on the separator for directing one corner thereof downwardly when the same is positioned for use.

5. The combination with an ink fountain including a fountain roller, a fountain blade and a support for the blade, of a separator for dividing the fountain into compartments, a pad interposed between the separator, the fountain blade and the fountain roller, means for securing the separator in position and a separable rocker piece in said separator for directing one corner thereof downwardly when the same is positioned for use.

6. The combination with an ink fountain including a fountain roller, a fountain blade and a support for the blade, of a separator for dividing the fountain into compartments, a pad interposed between the separator, the fountain blade and the fountain roller, means for securing the separator in position, said separator being grooved in its pad engaging faces, and a rocker on said separator for directing one end thereof downwardly when the same is positioned for use.

7. The combination with an ink fountain including a fountain roller, a fountain blade and a support for the blade, of a separator for dividing the fountain into compartments, a yoke for holding the separator in position in the fountain, means in the yoke for adjusting the separator, and a rocker on the separator for directing one corner thereof downwardly when the same is positioned for use.

8. The combination with an ink fountain including a fountain roller, a fountain blade and a support for the blade, of a separator for dividing the fountain into compartments, a pad interposed between the separator, the fountain blade and the fountain roller, a yoke for holding the separator in position in the fountain, and a rocker on the separator for directing one corner thereof downwardly when the same is positioned for use.

9. The combination with an ink fountain including a fountain roller, a fountain blade and a support for the blade, of a separator for dividing the fountain into compartments, having a bore and a slot therein, a yoke for holding the separator in position in the fountain including an extension engaging said bore and a slot engaging pin, and a screw adjustable to said extension for adjusting the separator.
